APPARATUS FOR HANDLING ASHES

Filed Sept. 27, 1926

UNITED STATES PATENT OFFICE

FRANK B. ALLEN, OF LOWER MERION TOWNSHIP, MONTGOMERY COUNTY, PENNSYLVANIA, ASSIGNOR, BY MESNE ASSIGNMENTS, TO THE ALLEN-SHERMAN-HOFF COMPANY, OF PHILADELPHIA, PENNSYLVANIA, A CORPORATION OF PENNSYLVANIA

APPARATUS FOR HANDLING ASHES

Application filed September 27, 1926. Serial No. 137,991.

This invention relates to apparatus for handling mixtures of solid and liquid material and more particularly to an apparatus for handling mixtures of ash and water, such as are produced by the use of water in removing ashes from furnaces.

An object of this invention is to provide means for diluting mixtures of solid and liquid material, so that the resulting mixture can be readily pumped.

Another object is to provide means for so preventing the settling of solid material carried by a liquid that clogging of the apparatus will be prevented.

Another object is to provide a reservoir into which a mixture of solid and liquid material may be delivered and from which it may be pumped with means for maintaining the level of the fluid mixture in said reservoir between predetermined limits.

Other objects will hereinafter appear.

The invention will be better understood from a description of one practical embodiment thereof illustrated in the accompanying drawings, in which,

Fig. 1 is a plan view of an ash handling apparatus in which the invention is embodied.

Fig. 2 is a longitudinal section of the apparatus shown in Fig. 1, and,

Fig. 3 is an elevation of a modified form of sump and pump.

A reservoir is shown at 1 and is provided with downwardly converging walls 2, one of which may be vertical, a bottom 3, and vertical walls 4 extending upwardly from the upper edges of the converging walls. Within the reservoir and substantially at the top of the inclined walls 2 are positioned horizontal gratings 5 extending over part of the upper surface of the reservoir. Around the horizontal gratings, upwardly extending vertical gratings 6 are provided. Two pipes 7 are shown as discharging into the space above the horizontal and within the vertical gratings and convey into this space mixtures of ashes and water brought from boiler furnaces or the like through suitable sluiceways 8.

The mixture of ashes and water passes downwardly through the grating into the bot-

tom of the reservoir. Large pieces of material will, of course, not pass between the bars and such pieces, therefore, remain upon the grating.

Adjacent the bottom of the reservoir is a conduit 9 to the inlet of a centrifugal pump 10 referred to hereinafter as the reservoir pump, by which the mixture may be pumped from the reservoir to a point of disposal. In order to prevent the solid material from settling in and around the inlet and clogging the same, a nozzle 11 has been provided extending into the inlet through which a jet of water may be admitted under high pressure to agitate the mixture and dilute it as it is being drawn into the pump, so that it may be readily pumped therethrough and to a point of disposal. As seen in Fig. 2 the nozzle 11 directs the jet of high pressure water in a direction opposite to the flow of the mixture through the outlet conduit 9. This high pressure jet agitates the mixture as it enters the discharge conduit and prevents the solid material from settling at the bottom of the hopper adjacent the conduit 9. The grating has its bars so spaced that pieces of material which are too large for pump 10 to handle will be retained upon the grating bars.

Within the reservoir is secured a vertical casing 12, in which a float 13 is adapted to move. The float is connected by rods to a lever arm 14 which operates an angle valve 15 which controls a water supply line 16 for admitting water to the hopper. This supply line may be connected to the pump 17 which supplies the water to the sluiceway nozzles 18 which water is mixed with the ashes as it enters the sluice conduit to the reservoir, or may be connected to any other supply of water. Preferably the reservoir pump is of slightly greater capacity than the discharge from the sluiceways to the reservoir. Therefore, no matter how much of the mixture of ashes and water is delivered to the reservoir, the reservoir pump will be able to dispose of it and maintain the contents below the top of the reservoir.

It will be seen that if the water in the reservoir drops below a predetermined level the float will move downwardly within its

casing and admit additional water to raise the level in the reservoir and conversely as the fluid level in the reservoir rises, this valve will be closed and permit the reservoir pump 5 to lower the level of the fluid in the reservoir.

The pumps 10 and 17 are driven by motors 19 and 20, respectively, which receive their current from a source of power G. A control 21 is provided by which both motors are 10 started and stopped and which preferably has an automatic relay, so that the sluice pump will not start until the reservoir pump has been started. A switch 22 may also be inserted in the power line to motor 19 and may 15 be operated by the movement of the float so that when the water level in the reservoir drops below a predetermined point, the reservoir pump will be stopped and remain so until the level reaches any desired point.

20 In Fig. 3, an inlet to the reservoir pump 10' is shown which consists of a 45° Y fitting 9', the branching arm of which is connected to the pump. The lower arm receives the nozzle 11' through which the agitating jet of fluid 25 is introduced. This may be conveniently attached by a plug, bushing, or the like.

While I have described one embodiment of my invention with some particularity, I do not limit myself to the precise details shown, 30 but claim as my invention all variations and modifications falling within the scope of the appended claims.

What is claimed:

1. An ash handling apparatus comprising 35 a tank, a conduit delivering a mixture of water and ashes to said tank, a pump supplying water to said conduit, a by-pass from said pump to said tank, a float-controlled valve in said by-pass, a second pump for discharging the mixture from the bottom of 40 the tank to a point of disposal, a nozzle in the intake of said second mentioned pump adapted to direct fluid against the flow of the mixture into said intake, and a source of fluid 45 under pressure connected to said nozzle.

2. An apparatus for handling a mixture of liquid and solid material comprising a receptacle, a conduit for supplying the mixture to the top of the receptacle, a grating 50 for removing large solid pieces from the mixture, float controlled means for maintaining the liquid level in the receptacle between predetermined limits, a conduit for discharging the mixture from the receptacle, and means 55 for injecting fluid under pressure into the discharge conduit in a direction opposite to the direction of flow of the mixture to agitate the mixture as it passes into the discharge conduit.

60 3. A disposal system comprising a receptacle adapted to contain a mixture of liquid and solids, an outlet leading from the receptacle, and means for injecting fluid under pressure into the outlet in a direction opposite to the flow of the mixture through the

outlet to agitate the mixture as it passes through the outlet.

4. A disposal system comprising a receptacle adapted to contain a mixture of liquid and solids, and having a converging bottom, 70 an outlet leading from the lower portion of the receptacle, means for injecting fluid under pressure into the mixture lodged in the apex of the converging bottom in the opposite direction to the flow of the mixture 75 through the outlet.

5. Apparatus for handling solid material comprising a receptacle, a supply of solid and liquid material opening into the upper portion of the receptacle, means for screening the material discharged from the supply into the receptacle, a water conduit opening into the receptacle, a discharge conduit leading from said receptacle, a pump connected with said discharge conduit for withdrawing the 85 mixture of solids and liquids from said receptacle, means for injecting a stream of fluid under pressure into said discharge conduit in a direction opposite to the flow of the mixture therethrough, a float valve associated with the water conduit and receptacle to control the supply of liquid to the receptacle, means for forcing liquid under pressure into the water conduit, and separate means separably operable from the same 90 point for actuating the pump at the lower part of the receptacle.

6. A disposal system comprising a receptacle adapted to contain a mixture of liquids and solids, an outlet leading from the lower portion of the receptacle and means for injecting fluid under pressure into the mixture at the outlet in the opposite direction to the flow of the mixture through the outlet. 100

In testimony whereof I hereunto affix my 105 signature this 25th day of September, 1926.

FRANK B. ALLEN.
